(57) **CLAIM**

I claim the ornamental design for a container having two openings, as shown and described.

DESCRIPTION

FIG. 1 illustrates a top rear right side perspective view of a container having two openings according to the present invention;

FIG. 2 illustrates a top front right side perspective view thereof;

FIG. 3 illustrates a right side elevational view thereof;

FIG. 4 illustrates a left side elevational view thereof;

FIG. 5 illustrates a front elevational view thereof;

FIG. 6 illustrates a rear elevational view thereof;

FIG. 7 illustrates a top plan view thereof; and,

FIG. 8 illustrates a bottom plan view thereof.

The broken lines in the drawings illustrate the portions of the design that form no part of the claim.
